Primary Examiner — Ian Simmons*Assistant Examiner* — Karra S Johnson(74) *Attorney, Agent, or Firm* — McHale & Slavin, P.A.(57) **CLAIM**

The ornamental design for a snow brush, as shown and described.

DESCRIPTION

FIG. 1 is a top front perspective view of the snow brush of the present invention;

FIG. 2 is a top view thereof;

FIG. 3 is a bottom view thereof;

FIG. 4 is a back view thereof;

FIG. 5 is a front view thereof;

FIG. 6 is a left end view thereof;

FIG. 7 is a right end view thereof;

FIG. 8 is a bottom front perspective view thereof;

FIG. 9 is also a bottom front perspective view thereof; and, FIG. 10 is top front perspective view thereof.

The broken lines shown are included for the purpose of illustrating portions of the snow brush that form no part of the claim.

1 Claim, 9 Drawing Sheets(56)
